STOCK INDICATOR.

No. 285,805.

Patented Oct. 2, 1883.

UNITED STATES PATENT OFFICE.

BRADLEY A. FISKE, OF NEW YORK, N. Y.

STOCK-INDICATOR.

SPECIFICATION forming part of Letters Patent No. 285,805, dated October 2, 1883.

Application filed May 17, 1883. (No model.)

To all whom it may concern:

Be it known that I, BRADLEY A. FISKE, a citizen of the United States, residing at New York, in the county of New York and State of New York, have invented certain new and useful Improvements in Electric Stock-Indicators; and I do hereby declare that the following is a full, clear, and exact description of the invention, which will enable others skilled in the art to which it appertains to make and use the same.

Stock-indications as at present made are printed upon strips of paper. In order to find at what figure any stock stands, it is necessary, therefore, to go up to the instrument and to read through all the quotations printed thereupon until the one sought is found. By my invention the names of stocks will be permanently affixed to a dial, and in plain sight, while opposite to each name will be clearly shown, through a slot cut in the dial, the figure at which the stock corresponding stands. This desirable result I accomplish by placing under a slot opposite the name of each stock a series of wheels, each wheel having imprinted upon its rim a number of figures, one figure of each wheel being visible through the slot cut in the dial. By revolving the wheels of any series, then, it is clear that different combinations of figures will be shown. By my invention these wheels are so revolved by electro-magnetic apparatus that the combinations shown through the slot opposite each stock indicate the figure at which that stock stands. I carry out this idea by the mechanism illustrated in the accompanying drawings, in which—

Figure 1 represents a front view of the indicator, the dial being cut away, as shown by the broken line, to expose the arrangement of the different series of wheels beneath, and the plate on which these rest being also cut away, as shown, in order to expose the actuating mechanism. Fig. 2 represents one series of wheels, upon the rims of which figures are painted. Fig. 3 is a vertical section of Fig. 1 on line $x-x'$. Fig. 4 is a diagrammatic plan view of the transmitter. Fig. 5 is a detailed view illustrating the manner of engagement of driving-wheels with one series of wheels.

Similar letters refer to similar parts throughout the several views.

The wheel w is supported upon the pivot p , and given a rotating movement by the action of a spring or weight in the box O acting through gearing upon the shaft p . This rotation is resisted by the escape-wheel e' and pallet e . The upper part of the pallet is a permanent magnet, and lies as a polarized armature between the poles of the electro-magnets e e' . When, therefore, alternating currents are sent through these electro-magnets, the escape-wheel e' , and with it the wheel w , is allowed to revolve. This causes the two driving-wheels s and s' to pass in succession under the first wheel t of each series of wheels; but projecting upward from the surfaces of s and s' are two edges, k and k' , while cut in the under surfaces of the wheel t , t' , &c., are corresponding grooves, which receive the edges k and k' . These edges k and k' pass then in succession through all the grooves cut in the wheels t , t' , &c. When k , for instance, lies in the groove of the little wheel t , it maintains toward t the same relation that a screw-driver does toward a screw in which it is inserted, so that if s is at that time given a half-revolution, t will also be given a half-revolution. The way in which s is given a half-revolution is by sending through the electro-magnet M a strong current. When this is done the armature a is attracted. This armature is attached to the pallet b , which engages with the ratchet-wheel r , so that when a is attracted r is turned one tooth. But the ratchet r is on the same shaft with the gear-wheels f and f' , and these in turn are geared to the driving-wheels s and s' , respectively. An attraction of a therefore causes s and s' to turn in opposite directions. Now, the number of teeth on the ratchet r is eight, and f and f' are four times as large as s and s' , so that each time the soft-iron armature a is attracted the driving-wheels s and s' are given a semi-revolution. Therefore, if k is inserted in the groove in t , t will receive a semi-revolution in one direction, while if k' lies in the grooves in t , t will receive a semi-revolution in the opposite direction. It is intended to have the distance between any two series of wheels (the distance between t and t'),

for instance) great enough to allow of inserting either k or k' in one of them without disturbing the other. The little wheels t t' , &c., are geared to the wheels u u' , &c., which are 5 four times as large, so that a half-revolution of t produces one-eighth of a revolution of u . Upon u are marked the fractions $\frac{1}{8}$, $\frac{1}{4}$, $\frac{3}{8}$, $\frac{1}{2}$, $\frac{5}{8}$, $\frac{3}{4}$, and $\frac{7}{8}$, so that each time a is attracted the fraction which appears under the slot is increased or decreased one-eighth, according to whether k or k' is inserted in the groove. Upon 10 y and z are marked ten digits each. u , y , and z are connected together in a well-known manner, shown in Fig. 2. A tooth projects from 15 the upper surface of u , which, once in each revolution, strikes one of ten teeth on the rear surface of y , while a tooth projects from the front surface of y , which engages once in a revolution with one of ten teeth on the back 20 of z . Therefore, ten revolutions of u produce one of y , and ten revolutions of y produce one of z . It is obvious that another wheel may be added to each or any series, if desired.

The manner in which this apparatus is controlled from a distant point can be seen from referring to Fig. 4, which represents a transmitter placed at a central station or other convenient point. By revolving the pointer P the polarity of the current sent to line by 25 the battery B is reversed by the well-known means represented, in which the escapement causes alternate contacts of H with L and L'. I do not limit myself, however, to this special method of transmitting alternating currents, 30 as this forms no part of my invention. The number of teeth in the escape-wheel D is such that a reversal of the current occurs each time the pointer P arrives opposite a point, A, A', or A'', &c., or twice for each stock. By 35 turning the pointer P, then, alternating currents are sent through the electro-magnets m' m' and M M, which, in the manner already described, causes the knife-edges k and k' to engage successively with the different series 40 of wheels arranged around the dial of the indicator. Suppose we move the pointer P until it is opposite the lower point, A, of the name "Erie." This (supposing the pointer and the wheel u of the indicator to be in 45 union before starting) will move the edge k into engagement with the train of wheels opposite to the name "Erie" in the indicator. Suppose, again, that we now move the pointer P until it stands opposite the upper point, A', 50 of the name "Erie." This will cause the edge k' to engage with the series of wheels opposite the name "Erie" on the indicator. If we now press the key K, this will add the current of the battery B', which will so 55 increase the magnetization of the electro-magnets M M that the force of the retractile spring q will be overcome and the number indicating Erie stock will be increased one-eighth. Had we pressed the key K while the pointer 60 P was pointing to the lower point, A, of the name "Erie," and while the edge k was en-

gaging the wheels, then the number indicating the value of Erie stock would have been diminished by one-eighth. If Lackawanna stock went down two-eighths, then the corresponding correction on the dial would be made by moving the pointer P to the lower point, A'', of the name "Lackawanna" and pressing the key K twice. If Lackawanna stock went up three-eighths, the correction on the dial would be made by moving the pointer P opposite to the upper point, A'', of the name "Lackawanna" and pressing K three times. 70

It is clear that in carrying my invention into practice one transmitter at a central station can be connected with any desired number of indicators placed in business-offices, hotels, &c., and that the indications of the value of each stock can be corrected from the central office whenever such stock goes up or 75 down, so that any person in sight of such an indicator can tell at a glance the value of any stock at that instant with the same ease and readiness that he can tell the time of day by glancing at the dial of a clock. 80

Having thus described my invention, what I claim, and desire to secure by Letters Patent, is—

1. An apparatus for presenting an indication of the figures at which stocks stand, in which the names of a number of stocks are shown upon a dial, and opposite each name the figures representing the value of that stock, said figures being upon the rims of wheels operated by electro-magnetic means, substantially as described. 90

2. The dial of a stock-indicator upon which are the names of stocks, in combination with a number of series of wheels upon the rims of which are placed figures showing through 105 slots in the dial in such manner as to indicate simultaneously the values of the stocks, and an electro-magnetic apparatus, by means of which any series of wheels can be operated in such manner as to change the figures on that 110 series of wheels, showing through the slot whenever the stock corresponding goes up or down, substantially as described.

3. The combination of a number of series of wheels having figures upon their rims, which 115 show through slots in the dial of a stock-indicator in such manner that the figures of each series thus showing indicate the figure at which that stock stands, with an electro-magnetically-operated driving-wheel mounted upon a 120 revolving frame or arm, and arranged to engage with each series in succession, and to give motion to any desired series, substantially as described.

4. The combination of the driving-wheels s 125 and s', secured to a frame or arm revolved by electro-magnetic apparatus, with a number of series of wheels upon whose rims figures are placed, in each series of which the driving-wheels s and s' engage successively as the arm 130 or frame revolves, as and for the purpose set forth.

5. The combination of the wheels t t' t'' , &c', arranged in a circle, with the driving-wheels s and s' , carrying the edges k and k' , said driving-wheels being mounted upon a frame or 5 arm revolved by electro-magnetic apparatus, as and for the purpose set forth.

6. A dial upon which are the names of stocks, in combination with a number of series of wheels upon which figures are placed, the 10 frame W , revolved by electro-magnetic apparatus, the driving-wheels s and s' , arranged to engage with each series of wheels in succession, the electro-magnets m' m' and M M , the escape-wheel e , and pallet e' , as and for the 15 purpose set forth.

7. The combination of the pointer P , escape-wheel D , pallet H , spring contact-arms L and L' , key K , batteries B and B' , electro-magnets M M and m' m' , line-wire l , revolving frame W , escape-wheel e' , pallet e , armature a , 20 ratchet-wheel r , pallet b , driving-wheels s and s' , edges k and k' , gear-wheels f and f' , series of indicating-wheels t u y z t' u' y' z' , &c., and the dial having names of stocks thereon, as and for the purpose set forth.
